COMBINATION KNIFE AND MONEY CLIP

Ernest C. Britton, Newington, Conn., assignor to The Lighter Corporation of America, Newington, Conn., a corporation of Connecticut

Filed June 1, 1961, Ser. No. 65,426

Term of patent 14 years

(Cl. D17—3)

FIG. 1 is a view of one side of a combination knife and money clip embodying my new design with the blades being shown in dotted lines in the extended position;

FIG. 2 is a view of the opposite side thereof with the blades being shown in dotted lines in the incased position;

FIG. 4 is a view of the other edge thereof;

The dominant features of my design reside in the portions shown in full lines.

I claim:

The ornamental design for a combination knife and money clip, substantially as shown and described.
